CLEANING DEVICE FOR SUBMERSIBLE BURNERS

Norman Swindin, London, England

Application February 4, 1946, Serial No. 645,392
In Great Britain September 18, 1944

11 Claims. (Cl. 158—120)

1

This invention relates to improvements in connection with submersible burners and has more particular reference but without limitation to such burners as are employed for raising the temperature of acid reagents such as are employed in steel pickling processes and of solution concentrators and the like.

In such applications the flame orifices of the burners tend to encrust with precipitated salts due to excessive evaporation of solvent at or adjacent to the orifice, and this precipitation tends to build until the orifice is closed and the burner ceases to function or even backfires.

The object of the present invention is to clear such deposits either automatically as occasion requires or according to a present time control for repeated operation whilst the burner is at work, and embraces the employment of a pricker whose action is to clear the jet orifice of obstruction.

It has been ascertained that submerged burner nozzles can be effectively cleared if the application of the pricker be sudden, or quickly repeated with a time interval between each multi-operation group of cleaning operations. Furthermore the tool or scraper employed must be such as to effect the required salt detachment without quenching the submerged flame.

The invention consists in an improved pricking device for cleansing the flame orifices of submerged flame burners, and means for operating same comprising in combination, a cleansing tool positioned when inoperative away from said burner, means for reciprocating said pricking device towards and into said flame orifice and means for producing operative reciprocation automatically either under time control or dependent upon the performance of the burner and after operation means for returning said pricker to its starting position.

The means for automatic operation of the reciprocating mechanism may embrace devices sensitive to fluid flow whereby variation in the rate of gas fed to the burner determines the instant of pricker operation, or the reciprocating mechanism may be under time control of an electrical and mechanical nature.

The cutting head of the pricking device must offer the smallest possible resistance to the gases issuing from the burner and a preferred form of the invention consists of a chisel-edged tube adapted to engage the interior walls of the burner nozzle and cut away any encrustation.

In order that the invention shall be better understood, reference is made to the accompanying drawings wherein:

2

Fig. 1 is a diagrammatic illustration of the invention in part sectional elevation showing means for automatic operation of the pricker device dependent upon the state of encrustation of the burner,

Fig. 2 shows in like manner to Fig. 1 a modified form of the means for automatic operation, Fig. 3 shows a further modification, and

Fig. 4 shows diagrammatically means for operating the pricker device under time control.

Referring to the drawing and to Fig. 1, the submerged flame burner 1 is of a known type mounted in an enclosed container 2 which is closed at the base and top and constitutes the tank of liquid to be concentrated, e. g. an acid pickling tank for steel. Gas supply to the burner is provided through conduit 4 wherein an orifice plate 5 is disposed constituting a device sensitive to gas flow to the burner jet. A static mercury switch 6 of the reservoir and rising tube type is disposed adjacent the orifice plate 5, and conduits 7 and 8 are led respectively the one 7 to the mercury reservoir 9 and conduit 8 to the rising tube 10. The rising tube 10 has electrical contacts 11 passing through a sealed joint controlling the supply circuit 12 for electrical energy to a solenoid switch 13.

The solenoid switch 13 is adapted to open or close an energising circuit to a static plunger solenoid 14, whose core extension rod 15 is linked to the extremity of rocker arm 16, said arm being pivoted at 17, and carrying at its other extremity a connecting rod 18 hinged to a compound piston valve 19 operating in the valve cylinder 20 of a valve box 21, of a fluid motor driven, for example, by a fluid under pressure such as compressed air. A fluid inlet port 22 is open to the piston valve cylinder 20 and passes therefrom to ports above and below the travel of the reciprocating main piston 23 operating in main cylinder 24. The exhaust ports 22a have an exit in part common to the inlet ports adjacent the working cylinder. Hence, upon movement of the compound piston valve under movement of the rocker arm 16 energising fluid is admitted to the working cylinder 24 to raise or lower the piston 23. Due to the positive stroke of the solenoid rod 15 the throw of the arm 16 compels the piston valve 19 to occupy one of two definite positions, i. e. it operates either to raise the piston or lower it. The piston 23 is fitted with a piston rod 25 passing through guide 26, said piston rod entering an aperture 27 in the submerged burner tank 2 and an arm 28 at right angles to the piston rod 25 carries the pricking tool 29. This latter consists of a heat

resisting alloy steel tube having chisel edges to cut, or squared-off edges to shear away incrustation formed within the burner body 1. Due to the fact that the burner container 2 is under pressure the piston rod 25 enters therein under a rubber or like sealing bellows as shown at 30. The said piston rod 25 also carries a trip arm 31 adapted to tilt the tail 32 of a pivoted time delay mercury switch 33, said switch 33 being adapted to break the circuit 12 to the solenoid switch 13 when the trip 31 tilts the tail 32 of the pivoted switch.

The operation of this form of the invention is as follows: According to the drawing, the pricking device 29 is at rest and the burner operating normally, the mercury level in 10 being depressed by the difference of pressure created by flow through the orifice plate 5, and the electrical circuit 12 open. The pricker is held at position shown by piston 23 which is subject to pressure. Should, however, the burner body get choked with incrustation the outlet for the flame decreases and less gas and air pass through the orifice plate 5 in gas conduit 4. This reduces the difference of pressure and mercury is displaced up the tube 10 closing contacts to the electrical circuit 12. This energises solenoid switch 13 closing main supply circuit to the plunger solenoid 14 which raises the arm 16 of rocker lever and thereby moves the piston valve downward admitting fluid to the underside of working piston 23 and raising same, exhaust of spent fluid issuing from exhaust port 22a on the upper side. Raising of the piston 23 equally raises the pricker 29 and inserts same within the burner body 1. Incrustation removed falls through the hollow interior of the pricker and the burner is cleared of obstruction. Assuming the pricker 29 to be at the end of its upward stroke, it must be returned to its lowermost position. This is effected as follows: The piston rod 25 in rising causes the trip 31 to tilt the mercury switch tail 32 and break the circuit 12 to switch 13. The core of solenoid 14 now drops and the position of the pricker is re-established to the position shown in the drawing, since the piston valve 19 rises and fluid is admitted and held upon the top of the piston. Should the burner not be cleared contacts 11 will remain closed, and operation of pricking will continue at the pre-determined interval of the time delay switch until the burner is clear of obstruction. The piston rod passing through the guide 26 may be rectangular in section to preserve alignment of the pricker head 29 with the burner 1. A further perforate guide nut 40 may be inserted about the entry point of the piston rod 25 to the burner chamber 2 or at any other convenient point, and the said rectangular section piston rod be articulated at 41, and provided with a slight twist 41a, which, on entry through a counterpart thread in nut 40, will impart a sufficient degree of rotation to the lower portion of the rod 25 and angularity to the pricker to clear the pricker 29 from the flame path of the burner. The amount of rotation may be only of the order of say 10 degrees.

In Fig. 2 the arrangement is somewhat simplified in that the second solenoid 14 is employed to operate the pricker rod, the core plunger 15 protruding above the solenoid body and used to operate the time-delay switch 32.

In Fig. 3 the solenoid 14 is replaced by a motor 43 adapted to energise a known type of thruster apparatus 44 wherein a horizontal centrifugal pump delivers fluid to a piston under pressure

which raises the thruster piston rod 45 to operate the arcuately moving lever 46 pivoted at 47 and raises the pricker rod. In this device the moment the time-delay switch 32 opens the solenoid switch circuit 12 the pump ceases to feed the fluid to the piston when the weight of the parts attached to the lever 46, and with the assistance of the spring 48 the piston drives the fluid through the pump vanes and finally occupies a zero position of rest as shown in the drawings. The operation otherwise is as described under Fig. 1.

In Fig. 4 the pricking device is shown as actuated by a pre-set timing device wherein a single phase electrical synchronously driven self-starting motor 50 is geared according to requirement to a rotary contact disc 51 wherein the stop and start contacts of two push button type of motor switch starters 52 and 53 are wired to the contact brushes 54, a common return circuit brush 55 completing the circuit. Under this arrangement time control current is fed to geared motor 56 to whose shaft 57 a crank 58 is fitted driving the pricker rod. The shaft 57 has a pinion 59 meshing with wheel 60, said wheel 60 carrying a trip pin 61, operating once per revolution the mercury switch 32. The leads 66 are taken to the brake 63.

Thus the synchronous motor constitutes the time piece and the time of dwell of the contacts on the circuit determines the duration of current supply to the pricker driving motor 56. The latter causes the pricker rod to reciprocate and the interrupter wheel 60 trips by pin 61 and bell crank lever 61a the switch 32 as previously described, interrupting the circuit to the motor 56. To ensure that the pricker 29 comes to rest in its zero position, and apart from accurate adjustment of the parts a peripheral electrical brake 63 comes into operation to engage a brake drum 64 mounted on the spindle of motor 56. The electromagnets of this brake are wired to the "stop" mechanism of the switch device 52.

By the above mentioned devices submerged flame burners can be maintained in a high state of efficiency during their operation, and what is equally important, blow outs, back fires and the time lost in cleaning the burner bodies or flame orifices is obviated.

I claim:

1. An improved pricking device for cleansing the flame orifice of a submerged flame burner, having in combination an electrical synchronous self-starting motor, a contact disc geared thereto, a power circuit switching device controlled by said contact disc and a motor, adapted to be energised by said power switching device, said motor driving a reciprocating pricker rod upwardly and downwardly through the flame orifice of the burner and tripping means geared to said motor for interrupting current to the power switching device and motor.

2. An improved pricking device for cleansing the flame orifice of a submerged flame burner as defined in claim 1, including an electrically controlled braking device operative to arrest the driving motor momentum when the burner pricking rod is at its lowermost position.

3. An improved pricking device for cleansing the flame orifice of a submerged flame burner, comprising a pricker tool reciprocable toward and away from the flame orifice of the burner, and means controlled by the flow of gaseous fuel to the burner for producing either one or a series of strokes of the pricker tool to clear away in-

crustation of the flame orifice according to the need therefor and as determined by the burner itself, the pricker tool being tubular for the passage of the flame therethrough during cleansing of the flame orifice.

4. A pricking device for cleansing the flame orifice of a submerged flame burner mounted in a chamber containing liquid to be concentrated comprising, in combination, a pricking tool mounted in said chamber for immersion in liquid therein and for upward and downward movement toward and into an inoperative position below and away from the flame orifice of the burner, means for reciprocating the pricking tool upwardly toward and into the flame orifice, and controlling means for said reciprocating means for automatically producing operative reciprocation of the pricking tool and for subsequently returning the pricking tool to its lower inoperative starting position below and away from the flame orifice of the burner.

5. A pricking device for cleansing the flame orifice of a submerged flame burner mounted in a chamber containing liquid to be concentrated comprising, in combination, a pricking tool mounted in said chamber for immersion in the liquid therein and for upward and downward movement toward and into an inoperative position below and away from the flame orifice of the burner, means for reciprocating the pricking tool upwardly toward and into the flame orifice and for lowering it to a position below said orifice, and controlling means for said reciprocating means for automatically producing operative reciprocation of the pricking tool, the latter comprising a tubular member having a cutting or shearing edge reciprocable axially into the flame orifice without obstructing the passage of the flame through the flame orifice.

6. A pricking device as defined in claim 4, wherein said controlling means is controlled by the flow of gaseous fuel mixture to the burner.

7. A pricking device for cleansing the flame orifice of a submerged burner comprising, in combination, a pricking tool movable toward and into an inoperative position away from the flame orifice, power means for reciprocating the pricking tool, a gas conduit to the submerged flame burner, an orifice plate disposed in said conduit, a primary power switching device for controlling said power means, a mercury switching device operating to open or close the primary power switching device in response to differential pressure on opposed sides of said orifice plate, a solenoid controlled by said primary power switching device and controlling the operation of the means for reciprocating the pricking tool,

and tripping means operative at the limit of travel of the pricking tool toward the flame orifice to open the power switching device and thereby cause return of the pricking device to its inoperative position.

5 8. A pricking device as defined in claim 7, wherein said power means comprises a fluid pressure operated piston connected to the pricking tool and a valve controlling it, said valve being operative at the termination of any operation of the pricking tool to cause the said piston to hold the pricking tool away from the flame orifice of the burner.

10 9. A pricking device for cleansing the flame orifice of a submerged flame burner comprising a pricking tool reciprocable toward and from the flame orifice of the burner, and means operative by reciprocation of the pricking tool for turning the pricking tool sufficiently to remove it transversely from the path of the burner flame when the pricking operation is completed and to move it into alignment with the flame orifice of the burner at the commencement of its cleansing operation.

15 10. A pricking device as defined in claim 9, wherein said pricking tool comprises an articulated rod, and said turning means comprises a spiral thread cut upon the length of said rod, and a correspondingly threaded static nut cooperative with said thread.

20 11. A pricking device for cleansing the flame orifice of a submerged flame burner, comprising a closed chamber enclosing the burner, a pricking tool within said chamber reciprocable toward and from the flame orifice of the burner and having an operating rod extending through a wall of the chamber to the exterior thereof, and an expandible and contractable flexible closed bellows having its ends connected respectively to the chamber wall and to the pricking tool rod and providing a fluid tight seal between the chamber and said rod.
